2 SHEETS—SHEET 2.

INVENTOR
Rudolph Winchel.

BY *Fred G Dietrich* ATTORNEYS

UNITED STATES PATENT OFFICE.

RUDOLPH WINCHEL, OF WEBB CITY, MISSOURI.

WHIRLING SEESAW.

1,398,166.

Specification of Letters Patent.

Patented Nov. 22, 1921.

Application filed March 8, 1921. Serial No. 450,540.

To all whom it may concern:

Be it known that I, RUDOLPH WINCHEL, a citizen of the United States, residing at Webb City, in the county of Jasper and State of Missouri, have invented certain new and useful Improvements in Whirling Seesaws, of which the following is a specification.

This invention has reference to improvements in that type of see saws adapted to have rotary or whirling motion imparted thereto during the operation of seesawing, and primarily it has for its purpose to provide a simple and relatively inexpensive construction of an amusement apparatus of the kind stated, that is more especially adapted for the amusement of children and which has special provision for permitting the use thereof with absolute safety.

Another object of the invention is to provide an amusement apparatus of the character stated, in which the several parts thereof are so designed whereby to adapt such parts for being readily and quickly assembled for use and easily knocked down for storing or shipping them.

Furthermore this invention contemplates, in a whirling see saw, a peculiar mounting of the rocking element or see saw, upon a central support whereby to provide for the application of a simple and effective means for sustaining the seats, at the opposite ends of the rocking element, in constant horizontal position and held that the rider's feet are so sustained that the act of applying the upward impulse to the rocking element, from the alternate ends thereof, imparts the desired rotary or whirling motion to the said rocking element as it is caused to swing in its up and down directions.

With other minor objects in view, herein-after apparent, my invention embodies, in an apparatus of the character mentioned, certain features of construction and novel combination of parts thereof, all of which will be fully outlined in the following detailed description, specifically stated in the appended claims and illustrated in the accompanying drawings, in which:

Figure 1 is a perspective view that illustrates my improved amusement apparatus at the limit of a see saw motion, the two beams that constitute the rocking element

being at their relatively edgewise closed position. 55

Fig. 2 is a similar view, the rocking beams being at a midway and relatively supported position.

Fig. 3 is a view similar to Fig. 1, the rocking element being shown tilted in the opposite direction. 60

Fig. 4 is a perspective view of the central or bearing portion of the rocking beam, the pivotal bearing member therefor, and the upper end of the standard upon which the said bearing member is sustained and has rotary movement, the said standard with the beams and the central support or bearing member being shown separated.

Fig. 5 is a detail cross section on the line 70 5—5 of Fig. 1.

Fig. 6 is a diagrammatic plan view of the apparatus hereinafter specifically referred to.

In the practical development of my invention a suitable base or central support is 75 provided, preferably in the nature of a tripod whose leg members 1 are joined at the upper ends by a metal cap 2, the said cap being suitably shaped for being secured to the leg ends by bolt and nut connections 80 3—3, as best shown in Fig. 4. At the lower ends the tripod legs are braced by tie rods 4 whose hook ends engage eye bolts 5 that are secured to the legs 1, the several connections mentioned being readily disconnected, 85 so the legs 1 and the cap member 2 may be quickly assembled or disconnected, as desired.

The rocking element, in my construction of see saw, consists of two beams 6—6 which 90 are disposed in edgewise vertical relation and each beam has a separate fulcrum or pivot mount, each of the mounts being in the nature of a cross bolt, the two bolts 7 being secured, one above the other, in the 95 bifurcated portion 80 of a metal bearing head 8, whose lower end terminates in a trunnion 81 that is adapted for being readily slipped into a central socket 20 in the cap plate 2, when the parts are assembled, as in 100 Figs. 1, 2 and 3, it being understood that when so placed the part 8 constitutes the support for the rocking element 6—6 (see-saw) and has rotary movement on the central bearing member or plate 2. 105

Each of the beams 6 has a plurality of

half round bearing seats 60 on the under surface thereof for engaging with their respective pivot bolts 7, the lowermost one of which bolts forms the fulcrum 4 and engages the 5 selected one of the seats 60 of the lower beam while the upper one of such bolts likewise constitutes the fulcrum for the upper beam 6.

The seats 60 in the lower edge of the 10 beams are located midway the length of their respective beam and they provide for adjusting such beams to adapt them for the desired leverage.

The said supports, in my construction of 15 see saw, are alike for each end of the apparatus and each of such supports consists of a pair of wooden uprights 9—9 located one at each side of their respective beam ends to which ends they are detachably secured 20 by nutted bolts 10—10 located one above the other and which pass through the ends of their respective beams 6, the said bolts forming the means for sustaining the uprights in a fixed vertical position as the beams are 25 rocked, and thereby support the seat boards 11—11 in horizontal positions, at all times, as the beams are swung up and down and whirled around in the manner presently explained.

30 The uprights 9—9 project above the ends of the beams 6 and to the upper end of each pair of uprights 9 is fixedly secured, in any suitable manner, a seat board 11, the said boards being positioned in the longitudinal 35 direction of the beams.

The inner end of each board 11 is longitudinally grooved as at 11^a to provide for seating onto the upper convex edge 62 of their respective ends of the upper beam 6 to 40 thereby permit the seat boards interlocking with the said upper beam ends when they reach the limit of their downward direction, as is clearly shown in Figs. 1 and 3.

45 Each seat board 11 has a hand hold 12 at each end thereof to enable the riders to hold themselves securely to the seat during the act of seesawing, the interlocking of the seat boards with their corresponding ends of the upper beam tending to take off undue strains 50 on the supports 9 when giving the down ends of the see saw the upward impulse during the act of seesawing.

When using the apparatus, the riders are positioned as indicated in the diagram, Fig. 55 6, and by reason of the manner in which the seat boards are sustained, with respect to the locking elements 6, and their connection with the upper beam, as stated, it follows 60 that as the rider at one end reaches the limit of the down position, with his feet engaging the ground, when pushing in the direction indicated by the arrows $a-a$ on Fig. 6, the down end of the see saw is caused to swing up as a rotary or whirling motion is 65 imparted to the rocking element, (the beams

6—6) in the direction of the arrow $b-b$ on the said Fig. 6, thus, at one operation, the act of causing the downward end of the see saw to swing up and to whirl the beams 6—6 around, is effected.

70 As the two beams 6—6 have individual fulcrums arranged in the same vertical plane, the two beams tend to close together as they pass their midway position in their up and down motion, and to open up as they 75 travel toward their said midway position. U-shaped metal guards 14 are provided, and they are attached to the under side of the upper beams 6 and have their pendent portions 14^a—14^a lapped over the upper edge 80 of the lower beam to close over the space between the beams as they separate, the guards being sustained along the beam sides sufficient distance to avoid danger of the 85 riders getting their hands or fingers between the beams while seesawing.

Wear plates are secured on each side of the beams 6—6 where they pass between the forked end of the supporting member 8.

90 From the foregoing description, taken in connection with the accompanying drawing, the complete construction, the manner of use and the advantages of my form of amusement apparatus will be readily apparent to any one familiar with the use of apparatus 95 of this character.

What I claim is:

1. In a see saw, a support, a standard held in said support to turn around a vertical axis, a beam fulcrumed on said standard to 100 rock on a horizontal axis and seats on said beam adapted to hold the users in a position transverse of the beam whereby, when the user pushes on the ground to rock the beam on its fulcrum the said beam will also be 105 pushed to whirl the said standard on its axis, said seats extending in the longitudinal direction of the beam and having handles at each end whereby the operators may sit 110 sidewise and grasp the handles of the seats.

2. In a see saw, a support, a standard held on said support to turn on a vertical axis, a pair of parallel beams mounted in said standard to rock on their parallel horizontal axes, seat members having seats, and 115 means connecting the adjacent ends of the said beams whereby to hold the seats level as the beams rock, said seats extending in the longitudinal direction of the beam and having handles at each end whereby the 120 operators may sit sidewise and grasp the handles of the seats.

3. In a see saw, a support, a standard held on said support to turn on a vertical axis, a pair of parallel beams mounted in 125 said standard to rock on their parallel horizontal axes, seat members having seats, means connecting the adjacent ends of the said beams whereby to hold the seats level as the beams rock, said seats ex- 130

- tending in the direction of the beams whereby the operator can sit sidewise of the beams and impart rocking and whirling motion to the beams, said seats extending in 5 the longitudinal direction of the beam and having handles at each end whereby the operators may sit sidewise and grasp the handles of the seats.
4. In a see saw, a support, a standard held 10 on said support to turn on a vertical axis, a pair of parallel beams mounted in said standard to rock the parallel horizontal axes, seat members having seats, means connecting the adjacent ends of the said beams 15 whereby to hold the seats level as the beams rock, and guard members on one beam to cover over the opening between the beams as they separate during the operation of tilting.
- 20 5. In a see saw of the character stated, wherein is provided a standard with parallel beams connected by vertical seat carry-
- ing bars at the ends of the beams; seats on the said bars having provision for receiving one of said beams when in the fully down- 25 wardly tilted position.
6. In a see saw, a support, a standard held in said support to turn around a vertical axis in either direction, a beam fulcrumed on said standard to rock on a horizontal 30 axis, seats having handles at the ends of the same, said seats extending in the longitudinal direction of the beam for holding the user in a sitting position transversely of the beam whereby when the user pushes on the 35 ground to rock the beam on its fulcrum said beam will be caused to whirl with said standard on its axis in either direction according to the transverse position in which the user is sitting, and means for maintaining said 40 seats horizontal at all times regardless of the position of the beam.

RUDOLPH WINCHEL.
